(57) CLAIM

The ornamental design for a pair of thigh high socks, as shown and described.

DESCRIPTION

FIG. 1 is a front view of a pair of thigh high socks shown with environmental structure;

FIG. 2 is a right side view of a pair of thigh high socks shown with environmental structure having a bent knee;

FIG. 3 is a second right side view of a pair of thigh high socks shown with environmental structure having a straight knee; and,

FIG. 4 is a right side view of a pair of thigh high socks shown without environmental structure.

The broken lines in the drawings are used to illustrate environmental structure that forms no part of the claimed design.
